UNITED STATES PATENT OFFICE

2,584,577

GARMENT

Robert O. Granert, Minonk, Ill.

Application May 28, 1949; Serial No. 96,121

2. Claims. (Cl. 2—93)

1

The present invention relates, generally, to new and useful improvements in coat garment construction, and relates particularly to a novel pocket formation in coat garments formed in a plurality of panels or sections joined together at the edges.

The invention is particularly useful in connection with men's suit coats, but may also be used in connection with women's and boys' suit coats, overcoats, and in fact coat garments, generally.

An important object of the invention is the provision of a new and improved coat garment construction wherein the coat garment is fabricated or made up from a plurality of relatively narrow panels cut according to pattern so as to give the desired form and fit when joined together, and wherein the coat garment has at least one side pocket located in one of the panels which is intermediate between two other panels, the pocket opening extending across the intermediate panel so that the ends of the pocket opening terminate at the opposite edges of the middle panel.

An important object of the invention is the provision of a novel method of making a pocket in a panel which is to be joined with other panels in the making of a coat garment.

Still another important object of the invention is the provision of a novel type of coat garment construction, particularly men's and boys' suit coats, said novel type construction permitting the coat garments to be produced at reduced cost due to reduction in waste material, ease and increased rate of fabrication by workmen not having the skill required by present methods, with the production of a superior garment with respect to appearance, form and fit, and permanency of shape.

Certain other objects of the invention will, in part, be obvious and will, in part, appear hereinafter.

For a more complete understanding of the nature and scope of the invention, reference may be had to the following detailed description thereof taken in connection with the accompanying drawings, wherein:

Fig. 1 is a plan view of the left front panel for the left side of a man's suit coat;

Fig. 2 is a plan view of an intermediate panel which is to be attached to the panel in Fig. 1;

Fig. 3 is a view of still another panel which is to be attached to the panel shown in Fig. 2;

Fig. 4 is a view of a pocket piece which is to be used in making a side pocket in the panel shown in Fig. 2;

2

Figs. 5 through 11 are perspective views illustrating the several steps involved in making a pocket in the panel shown in Fig. 2 in accordance with the method of the present invention; and

Fig. 12 is a view showing the three panels in Figs. 1, 2 and 3 joined together along the vertical edges so as to form the left side of a man's suit coat.

10 Heretofore, coat garments, such as men's suit coats, have been formed in a more or less standardized or conventional manner which is fairly universal in the garment trade. Briefly, each side of a coat garment is now formed of a single piece of material which extends from the front edge of the coat around to the back. The back of the coat may be formed of a single piece which joins together the two sides, but, generally, the back is formed in two pieces. The sides of the coat and the back pieces or panels are all joined together along the corresponding edges thereof as can be readily seen by inspection.

15 In the prior methods of making coat garments, the side pockets are formed, in known manner, in one or both of the coat side pieces. Considerable skill is involved in forming the pockets so that they come out properly, will not give away at the edges in use, and will not have unsightly gathering or ruffles along the edges of the opening.

20 Furthermore, when the side of a coat garment is formed of a single piece, as is the current practice, it is difficult to impart into the garment proper shape and form. Thus, a flat piece of material is started with and it is necessary to come out with a formed shape on piece of material. At the present time, such form and shape are obtained by resorting to the use of so-called darts, steam pressing on forms so as to distort the material from its normal condition, padding, etc. Considerable skill is involved in such forming operations and the quality of the job depends greatly on the quality of the material used, the skill and time taken to perform the forming operations, all of these factors contributing materially to the cost of the garment.

25 According to my present invention, I have provided a novel type of coat construction which permits a superior or high quality garment to be produced, using any desired coat material even though considered normally very difficult to work with, and using workmen who are relatively unskilled, but who, by reason of the simplicity of the forming operations, are able to turn out a superior garment at production rates

in excess to those now obtained using highly skilled operators and tailors.

The garments made in accordance with the present invention fit much better than garments made according to conventional methods, the material is not stressed or deformed to anywhere near the present degree, and the garments retain their shape much better during a longer life, and less frequent pressing is required. One of the important details which accounts for the easier construction at lower cost of garments made in accordance with the present invention, is the side pocket construction which may be adopted with a high degree of uniformity and quality even by relatively unskilled operators, whereas, previously, such pocket formation called for some of the highest skill involved in the garment-making operations, and even then, was at best a slow and time-taking operation.

In order that the nature and details of the present invention may be more fully described, reference may now be had to the following description wherein reference is made to the several figures of the drawings.

Referring first to Figs. 1, 2 and 3, relatively narrow panels, 5, 6 and 7 are shown which are cut out from a suitable piece of garment material following panel patterns established for the particular size and style of coat garment being produced. It will be noted that the panel 5 serves as the frontmost panel of the left-hand side of the coat to be formed, the panel 6 constitutes the intermediate panel for the left side of the coat, and the relatively narrow panel 7 constitutes the back or rear panel of the left-hand side of the coat.

In order that the panels 5, 6 and 7 may be properly and accurately joined together, as will be more fully described hereinafter, it will be noted that each of the edges to be joined bears several index markings which are correspondingly spaced. These markings are readily made when the panels are cut out by following the marking notches formed in the respective patterns.

The markings designated as *p-p* in panel 6 serve as the guide marks for forming a pocket in this panel according to the technique which will now be described in connection with Figs. 5 through 11.

The first operation in forming a side pocket in the intermediate panel 6 is the marking off of graduation marks *a*, *b*, *c*, and *d* on opposite sides of the pocket marks *p*, as shown in Fig. 2. A suitable dimension for the spacing between each of the marks *a*, *b*, *p*, *c* and *d* is $\frac{1}{16}$ of an inch. However, it is to be understood that this dimension is mentioned for purpose of illustration and that other dimensions for the spacing of the guide marks may be used, as desired.

The pocket in the panel 6 is formed from a pocket piece 8, shown in Fig. 4. The piece 8 is rectangular in configuration and is formed of a suitable pocket lining material such as rayon, silk, nylon, or other desired material. A fabric material known as "silesia" is normally used for the pocket piece 8. End pieces or facings 10 and 11 are sewed at opposite ends of the pocket piece 8, the pieces 10 and 11 being normally formed of the same fabric material as that from which the coat panels 5, 6 and 7 are cut out. If the material has a pattern, such as a stripe which runs vertically in the

finished garment, the facings 10 and 11 are cut so that the strips extend horizontally.

After the pocket piece 8 has been formed and the panel 6 marked on opposite sides of the pocket marks *p*, as described, the first operation in forming the pocket is shown in Fig. 5. In this step, the panel 6 is laid down flat in the position shown and the pocket piece 8 is laid thereover with the bottom facing 11 folded upon itself and with the fold 12 being aligned with the marks *d-d*. The three thicknesses of material are now stitched together or piped along line *c-c*, this seam being indicated in Fig. 5 by the broken line 13.

In the next operation, which is shown in Fig. 6, the pocket piece 8 is turned down as shown and the upper end of the end piece 11 is folded back on itself, as shown, so that the fold line 14 is aligned with the graduation marks *a-a*. The three thicknesses of material are now stitched or piped along line *b-b*, this piping seam being indicated by the broken line 15.

The next operation is shown in connection with Fig. 7 and involves completely cutting across the panel 6 along pocket line *p-p* and at the same time cutting through the one thickness of the end piece 11 lying between seams 13 and 15. After this cutting or severing operation the folds 12 and 14 are turned out or over, as shown, in Fig. 8, so that the folds 12 and 14 are opposed. The pocket piece 8 is then turned back under upon itself so that the facing 10 comes up under the several thicknesses of material at the fold 14, in the manner shown in Fig. 9. The facing 10 is now stitched through one or more of the underlying thicknesses of the portion of the end piece 11 which has been left at the fold 14.

Having completed these operations, the next operation is to place the two fold lines 12 and 14 together as shown in Fig. 10 making sure that the side edges of the panel 6 are aligned and having the panel 6 look just the same as it did initially, except for the presence of the piping and folds 12 and 14. It will be noted that no change is made in the overall length of the panel 6 as a result of the pocket forming operation. Basting stitches may be used to maintain the piping folds 12 and 14 joined together in aligned relationship as shown in Fig. 10. It is also desirable to attach the opposed piping folds 12 and 14 together at opposite ends of the pocket as indicated by the stitching marks 19-19. In the next operation the lower portion of the panel 6 which extends below the fold 14 is turned up out-of-the-way as shown in Fig. 11 and the pocket is closed at the sides by sewing along the broken line designated at 16. In one construction, the tacking stitches 19-19 may be located approximately $\frac{1}{4}$ of an inch in from the outer edge and the pocket stitching line 16 may start at the top of the pocket inwardly about $\frac{1}{2}$ of an inch from the outer edges and then flare out so as to come within $\frac{1}{4}$ of an inch of the sides of the pocket seam 8. It will of course be understood that these particular dimensions are given by way of illustration and are not critical.

With the completion of the stitching of the line 16, the formation of the pocket in the panel 6 is completed. In the next operation, any material of the pocket piece 8 which extends beyond the side edges of the panel 6 are trimmed off and then just below the fold line 12 the under thicknesses of the facing material 11 is notched inwardly approximately to the stitching line 16

so that these under thicknesses at this edge may be turned in out-of-the-way when the panel 6 is joined to the other panels 5 and 7.

In joining together the panels 5, 6 and 7, the corresponding index marks are aligned and the edges of the material are turned in so that the panels may be joined together from the back side with only a seam line showing from the outside. That is the conventional manner of joining together coat panels or similar pieces of material. It will be noted that the edges of the panel pieces 6 and 7 are not straight, but rather are somewhat irregular. When the panels are joined, this configuration serves to give the desired form or fit to the side of the garment formed by these panels when they are joined together. Dart lines and similar forming operations are thus eliminated.

The completed left side of the coat is shown in Fig. 12. It will be noted that the side pocket is disposed entirely within the panel 6 and that the opening of the pocket formed by the fold lines 12 and 14 extends clear across this panel.

It will be noted that the pocket thus formed in the panel 6 and left-hand side of the coat garment involves sewing only along straight lines, and not on a bias, and cutting along straight lines with clear guide marks. Such operations can be accurately and quickly carried out by operators having only a small amount of training who are far from being skilled tailors.

It will be understood that the right-hand side of the garment may be formed in a similar manner using three panels corresponding to panels 5, 6 and 7 but reversely shaped. Similarly, another side pocket will normally be formed in the right-hand side of the coat garment. This pocket may have a cash pocket in it if it is desired. After the two sides of the coat garment have been thus formed, they may be joined with the back panel or panels so as to complete the forming of the garment except for the addition of the sleeves which may be added on in known manner.

It will be understood that the pocket in the panel 6 may be formed in accordance with other procedures, also, it will be appreciated that different styles of pockets may be formed, such for example as a pocket having a flap which covers the pocket opening. However, the essential feature is to have the pocket opening extend across the full width of the intermediate panel 6.

It will also be understood that more than three panels may be used in forming the side of a coat. However, in any case the side pocket should be formed in one of the intermediate panels.

Since certain further changes may be made in the foregoing construction and different embodiments of the invention may be made without departing from the spirit and scope thereof, all matter described above or shown in the accom-

panying drawings is intended to be interpreted as illustrative and not in a limiting sense.

I claim:

1. In the method of making a coat garment formed by a plurality of panels joined together at the edges, the improvement which comprises, cutting out at least three panels which are to be joined together along the side edges with one of said panels adapted to be disposed intermediate two others, folding one end of a pocket piece along a fold line which extends at a right angle to the length of said pocket piece, disposing said folded end on said intermediate panel in such a way that said fold line extends parallel to a line on said intermediate panel coinciding with the pocket opening to be formed therein with said fold line being disposed below said pocket opening line a distance x and with the main length of said pocket piece being uppermost and extending upwardly from said pocket line, stitching said fold to said panel along a line intermediate said pocket line and said fold line and parallel thereto, folding the free end of said pocket piece adjacent said fold upon itself so as to form a second fold line disposed above said pocket line a distance of approximately x with said second fold line being parallel to said pocket line and with the said free end of said pocket piece being uppermost, stitching said second fold to said intermediate panel along a line intermediate said second fold line and said pocket line and parallel thereto, completely severing said intermediate panel and the single thickness of said pocket piece which lies thereover along said pocket line, turning said first and second fold lines toward each other, securing the free end of said pocket piece opposite said folded end to said intermediate panel material adjacent said second fold line thereby folding said pocket piece upon itself along a line crosswise to the length thereof and approximately midway between the ends thereof, securing said first and second fold lines in even opposed registering alignment, and stitching the folded pocket piece along the open sides thereof so as to close said pocket, said distance x being only a small fraction of the width of said intermediate panel at said pocket line.
2. The improvement called for in claim 1 wherein each of said lines of stitching is located a distance of approximately one-half x from said pocket line.

ROBERT O. GRANERT.
